UNITED STATES PATENT OFFICE.

WILLIAM D. LINTON AND HIRAM W. FARMER, OF PATOKA, ILLINOIS.

DESIGN FOR A HOG-RING.

SPECIFICATION forming part of Design No. 29,107, dated July 26, 1898.

Application filed June 23, 1898. Serial No. 684,304. Term of patent 7 years.

To all whom it may concern:

Be it known that we, WILLIAM D. LINTON and HIRAM W. FARMER, citizens of the United States, residing at Patoka, in the county of Marion and State of Illinois, have invented and produced a certain new and original Design for Hog-Rings; and we do declare the following to be a full, clear, and exact description of the invention, such as will enable others skilled in the art to which it appertains to make and use the same.

The invention has relation to a design for hog-rings; and it consists of a ring of the configuration shown in the accompanying drawings, in which—

Figure 1 is a perspective view, and Fig. 2 is a front view.

The leading feature of the design comprises an elliptically-curved body portion 1, having tapering points 2, a swell tapering portion 3, and upwardly-projecting diverging points 4.

What we claim is—

The design for a hog-ring as herein shown and described.

In testimony whereof we have hereunto set our hands in presence of two subscribing witnesses.

WILLIAM D. LINTON.
HIRAM W. FARMER.
